UNITED STATES PATENT OFFICE.

BENJAMIN J. HARTMAN, OF WOOSTER, OHIO.

HARNESS-SADDLE.

SPECIFICATION forming part of Letters Patent No. 281,501, dated July 17, 1883.

Application filed March 3, 1883. (No model.)

To all whom it may concern:

Be it known that I, BENJAMIN J. HARTMAN, a citizen of the United States, residing at Wooster, in the county of Wayne and State 5 of Ohio, have invented certain new and useful Improvements in Harness-Saddles; and I do declare the following to be a full, clear, and exact description of the invention, such as will enable others skilled in the art to which 10 it appertains to make and use the same, reference being had to the accompanying drawings, and to letters or figures of reference marked thereon, which form a part of this specification.

15 Figure 1 of the drawings is a vertical sectional view of my saddle. Fig. 2 is a plan view of the pad-plate A, and Figs. 3 and 4 are detail views.

This invention has relation to harness-saddles or coach-pads; and it consists in the construction and novel arrangement of the square opening or recess in the pad-plate, near its end, and the staple-shaped fastening adapted to engage said opening or recess, connecting 25 the skirt-leather to the plate near the extremity of the latter; in providing a rise in the end portion of the plate when the opening or recess is made, all as hereinafter set forth.

20 In the accompanying drawings, illustrating this invention, the letter A designates the pad-plate, having the longitudinal rim-flanges b. The outer ends of the plate are depressed, as indicated at c, to the depth of about one-quarter of an inch from the top of the rim-flange, to form a recess seat or boxing for the attachment ends d of the skirt-leathers E.

25 At the inner end of the depression or seat c is a shoulder, g, rising to the higher middle portion of the plate, (indicated at h.) The height of this shoulder is about equal to the thickness of the skirt-leather E, so that when its attachment end d is in position its upper surface will be flush with the middle bearing-surface of the plate. There is therefore no necessity of shaving or skiving and thus weakening the end of the skirt-leather.

Near the end of the bearing c is formed 45 a wave-like rise, r, in the pad-plate, which is designed to relieve somewhat the strain on the

fastenings whereby the skirt-leather is attached to the plate, as well as the strain on the perforated portions of the leather itself.

K represents the pad-screw, which passes through the cap-leather l and skirt E, and through the perforation m of the pad-plate in- 55 to the nut in the pad below.

Through the pad-plate, or in the same, near its end, is formed a squared or rectangular opening or recess, to receive the lower branch of the staple-shaped fastening P. Usually it 60 is preferred to make a square opening through the plate, as indicated, s, said opening having an inclined offset bearing, s', communicating therewith on the under side of the plate, toward its end, and on the upper side of the 65 plate an inclined offset bearing, s'', extending toward the middle of the plate. The staple-shaped fastening P is formed with a broad or flanged head, t, which is connected by the squared shank portion or bend v to the wedge 70 form under branch, z. In order to connect the fastening P to the skirt-leather, a perforation is made through the main strap, and the lower branch and shank v are passed through until the flanged head rests on the surface of 75 the skirt-strap. The cover-strip a' is now stitched to the main skirt-strap, concealing the head of the fastening and holding it in place. The leather is now applied to its bearing in the end of the plate, the lower branch 80 of the fastening P being passed through the opening s, to engage the under bearing or offset recess, s', while the squared shank engages the opening itself. Then the pad-screw is inserted and screwed up. The fastening P serves 85 to secure the skirt in position at the end of the plate firmly, preventing it from becoming detached. It also prevents rocking or side motion of the skirt-leather.

Having described this invention, what I 90 claim, and desire to secure by Letters Patent, is—

1. In a harness-saddle, the staple-shaped fastening P for the skirt-leather, having the flanged head, squared shank or bend, and 95 wedge-form lower branch, substantially as specified.

2. In a harness-saddle, the pad-plate hav-

ing a squared opening or recess near its end, in combination with the staple-shaped fastening *p*, whereby the skirt-leather is connected to the pad-plate near its end, substantially as 5 specified.

3. The pad-plate having the curved rise *r* near its end, and the recess or opening *s* for the skirt-fastening extending through said rise, substantially as specified.

In testimony whereof I affix my signature in 10 presence of two witnesses.

BENJAMIN J. HARTMAN.
